UNITED STATES PATENT OFFICE

WILLIAM H. HARDY, OF FORT WORTH, TEXAS

CUSHION FOR OFFICE FURNITURE

Application filed March 2, 1927. Serial No. 172,083.

This invention relates to cushions for office furniture or fixtures, and more particularly for installation on waste baskets, cuspidors and the like, and has for an object the provision of novel means for cushioning the exposed or protruding parts of waste baskets and fixtures, in order that should they be handled carelessly and be brought into contact with furniture, they would not mar the furniture or fittings of an office.

The invention is furthermore designed to guard against injury to wearing apparel which might become caught or snagged through the presence of unprotected rough surfaces of office equipment.

It is a further object of this invention to provide a cushion of the character indicated which may be expeditiously applied to waste baskets and the like now in common use, or they may be made part of new equipment; and it is a still further object to produce the cushions of any length suitable to be cut to fit the circumferences of waste baskets, cuspidors or fixtures, in order that the cushions may be fitted to such office equipment. Instead of having the cushion made in strips, it may be desirable to make the same ring-shaped of suitable diameter to fit articles of predetermined sizes.

This guard is designed to be applied to metallic, reed and wire furniture, particularly for use upon such articles where the base or supporting rim has projections or joints and are constantly handled or moved. The construction of the cushion rim is such that in use means are provided for engagement with encircling members of the bottom ring of the article and with the strands or rods which are attached thereto, the cushion rim not only serving its main object, but also serving to more securely connect the parts of the base to which my improvement is applied.

It is furthermore an object of this invention to produce a cushion having novel means by which it is frictionally retained in place on the object to which it is applied, and to produce a cushion which is simple in construction and comparatively inexpensive to manufacture.

It is a further object of this invention to provide the elastic cushion with internal ribs which are parallel and are spaced to engage encircling members of the structure, as strands or bars which extend beyond the circular member which is embraced by such strands or bars, substantially as shown.

With the foregoing and other objects in view, the invention consists in the details of construction, and in the arrangement and combination of parts to be hereinafter more fully set forth and claimed.

In describing the invention in detail, reference will be had to the accompanying drawings forming part of this application where-in like characters denote corresponding parts in the several views, and in which—

Figure 1 illustrates a view in perspective of a portion of a waste basket with a device embodying the invention applied thereto; 70

Figure 2 illustrates a sectional view thereof; and

Figure 3 illustrates a perspective view of a fragment of the cushion.

In these drawings, 5 denotes a conventional type of waste paper basket having a reinforcing rim to which a cushion 6 is applied.

The cushion, in the present embodiment of the invention, consists of a yieldable body having a channel 7 extending longitudinally thereof. The cushion is preferably approximately round in cross section, although it is provided with extensions 8 and 9 which converge and terminate in slightly spaced relation to each other, although when new and before the material is manipulated, as it would be in applying it to a basket or the like, the surfaces of the converging portions may be in contact.

The cushion is made of relatively rigid material and preferably of tough rubber composition in order that the converging portions of the cushion may be spread apart to straddle the edge of a rim of a cuspidor or a wire or ledge of a basket, and it is the purpose of the inventor to have the material of such strength as to cause the converging portions 8 and 9 to press the object to which they are applied and thereby cause the retention of the cushion by friction. In order to augment the fric- 100

tional engagement of the cushion and the object to which it is applied, the converging portions 8 and 9 are provided with longitudinally disposed ribs 10 and 11 on their inner surfaces, and when these engage a flange or other part of an object to which the cushion is applied, they will resist dislodgment of the said cushion.

It will be apparent from an inspection of the drawing that if a cushion as shown in Fig. 3 is manipulated to separate the converging portions 8 and 9, the clearance between them will be sufficient to receive the head of a basket or the flange of a cuspidor or other like element, and when released, they will contact the said object with sufficient force to cause the retention of the cushion when in use.

The cushion-rim hereinbefore described, when applied to circular objects as shown in Fig. 2 of the drawings, will be provided with inwardly extending projections or ribs 10 and 11 disposed, as shown, the object of these projections being to provide a dead air space or channel, thereby producing a seal about the major portion of the member 5. This channel prevents the circulation of air, and it is well known that a cushion of the character shown contains sulphur, and when exposed to air, rapidly deteriorates as to elasticity, owing to the oxidation of the rubber. In a device of this character, it is very desirable that this should be prevented, as the wear in use is so small that it lasts for an indefinite time.

I claim:

A cushion for office furniture consisting of an elongated approximately semi-tubular member whose edges merge into coacting jaws, longitudinally extending ribs on the inner opposite surfaces of the jaws near their junction with said member, adapted to engage the surfaces of a round object encompassed by the member, and oppositely disposed projecting parallel ribs on the jaws near their edges adapted to contact with a part projecting from the part of the structure engaged by the first mentioned ribs.

WILLIAM H. HARDY.
